OFFSET PRINTING PRESS

Irving A. Hunting, South Plainfield, N. J.

Application September 16, 1939, Serial No. 295,197

12 Claims. (Cl. 101—144)

This invention relates primarily to lithographic sheet-fed offset printing presses, but some features may be used on other kinds of printing presses and for the feeding of sheets of paper for other operations.

The main object of this invention is to provide a press which can print a larger sheet for a given size of cylinder and run faster and more smoothly than presses now in general use.

Another object is to leave the plate and impression cylinders with fixed axes and to trip the blanket cylinder from one, and then the other, while the gap, or the part of the cylinder not used for printing, is adjacent to either cylinder.

To accomplish these and other objects it is necessary to register the sheet as it is passing from the feed pile to the impression cylinder, and not, as in common practice, to stop the sheet to register it and then take the standing sheet by the moving cylinder. It is also necessary to arrange a trip which can take more time for separating the cylinders, if a sheet is missed, and yet will allow more time for printing.

To this end I have arranged the centers of the impression and blanket cylinders in a horizontal line and the plate cylinder vertically above the blanket cylinder, and I have arranged a trip operated by a cam attached to the impression cylinder shaft whose operating surface acts in about one quarter of the time required to turn one revolution. In this time the blanket cylinder is tripped from, or to, an adjacent cylinder, leaving the other three-quarters of the cylinder for printing.

In order to be able to trip the blanket cylinder in two directions at different times I support its bearings in stirrups swung from eccentric spindles extending through the frames below the plate cylinder bearings and hold it in relation to the impression cylinder by links from similar eccentric spindles located between the blanket and impression cylinder bearings.

At the time the sheet is being taken by the grippers at the top of the impression cylinder, the plate is beginning to print on the blanket, and the blanket lacks a quarter turn of starting to print on the sheet. At this time if a sheet were missed, there would not be time to set the trip and to trip the blanket cylinder away from the impression cylinder, nor is it the right time to trip it from the plate cylinder. Therefore I am running the sheet from the feed roller near the supply pile at essentially the cylinder surface speed and then electrically detecting the absence, or misplacement, of an insulating sheet between two rolls placed between the impression cylinder

and the feed roller. This gives time for detection, for setting the trip, and for tripping the blanket cylinder from the plate cylinder as the gaps pass. Then this tripping action sets the trip for tripping the blanket cylinder from the impression cylinder while the gaps are passing.

The sheet, when taken from a pile by any suitable means, is fed forward on a smooth table at a uniform speed, about the same that it will have after being taken by the cylinder. As the sheets will not advance in exact register, they are timed to come a little too late to reach the cylinder in register, and then in the last part of their straight travel they are pushed forward a little faster till they reach front register stops moving on a reciprocating carriage at cylinder speed. This carriage also has a side register stop, past which the sheet is fed and then pushed over against the stop before being taken by the cylinder grippers.

The carriage that carries the front and side registers is driven by a modified crank and connection at either end. These drive the carriage forward at the speed of the cylinder, while the sheet is being registered and transferred to the impression cylinder.

This carriage also supports friction elements, which, with the carriage, are lowered on to the sheet as it is being advanced at cylinder speed. These friction elements have a supplemental motion to push the sheet over the table against the register stops.

I have shown my invention in the accompanying drawings in which:

Figure 1 is a side view of a sheet-fed offset printing press showing the feed and the cylinders with the tripping mechanism.

Figure 2 is a section on lines A—B—C—D of Figure 1 through the gears driving the feed carriage crank.

Figure 3 is a section on lines E—F—G of Figure 1 through the gears driving the detecting wheels.

Figure 34 is a top view of parts shown in Figure 33.

Figure 35 is a horizontal section of the register driving gear and clutch.

Figure 36 is a section on line 36—36 of Figure 35 looking in the direction of the arrows.

In these drawings each reference character 55 designates the same part wherever shown.

The front frame 50, with a similar rear frame, supports the cylinders and other parts of a sheet-fed lithographic offset printing press. The impression cylinder 51 takes and supports the sheets to be printed from a blanket 206 on the blanket cylinder 52. This receives its print from the form on a metal plate 204 held in the plate cylinder 53. The inking mechanism is shown diagrammatically as 54, and the water rollers as 55. The delivery 56 takes away the printed sheets. The sheet is taken from the cylinder grippers 57 and carried over the path 58 by grippers in a gripper bar carried by chains 59 around sprockets 60. The cylinders are shown with bearers 250 which roll together.

The sheets are taken from the pile 61 by the commonly-used sucker 62, or any other convenient method, and carried to the feed roller 63 under friction rolls 64. This roller is driven at

cylinder speed by gear 65 and intermediate gear 66. The usual tapes 67 pass around this feed roller and over the feed table 68 which may be composed of flat bars of steel 69 resting on bars 70 extending between inside frames 71. These frames are carried on still shafts 72 and 73. Pulleys 74 held in brackets 75 attached to a bar 70 reach up through the table 68, receive the tapes, and return them under the table to roller 63. To keep the sheets moving at cylinder speed, small spring-pressed friction rolls 76 held by arms 77 and brackets 78 are used (see Figure 29). These may be placed where desired on rods 79. These rods are held above the table over the sheet path by brackets 80 on rod 72. This rod also carries arms 81 for holding the friction rolls 64.

Thus the sheet is kept moving at cylinder speed till it approaches the cylinder; then the sheet is moved along the table by friction elements held on a reciprocating carriage. These friction elements rest on the sheet while the carriage is moving at cylinder speed and slide the sheet over the table to bring it to the cylinder in registered position.

This carriage 82 is reciprocated by connecting rods 83, one at either end of the carriage, operated from crank pins that have crank arms of varying length to drive the carriage at the uniform cylinder speed while the friction elements have control of the sheet.

The impression cylinder 51 has gears 84 at either end, and these, through the intermediate gears 85, 86, 87, and 88, drive gears 89 at cylinder speed. These gears 89 (see Figures 15, 16, and 10) run on studs 90 and carry slides 91 in guides 91', and these slides carry crank pins 97 to operate connecting rods 83 and reciprocate the carriage by studs 83'. The position of this slide on either end determines the length of the crank arm, and it is controlled by the fixed cam 92, in which cam roll 93 runs. This roll is carried on stud 94 extending from the slide 91 through block 95, which slides in slot 96 in gear 89. This cam is so formed that when the cam roll 93 and crank pin 97 are passing the vertical center line of gear 89, the crank arm is equal to the radius of the impression cylinder, and the crank pin 97 and the carriage 82 are moving at cylinder speed. At either side of this vertical line the crank arm is lengthened just fast enough to keep the carriage moving at the uniform cylinder speed, while the friction elements are controlling the sheet. Then the crank arm is so controlled that the carriage is smoothly stopped, returned, and brought forward to cylinder speed again.

As to the register carriage 82, see Figures 18 and 19. This is composed of a pair of ends connected by a bar 98, the front end 99 being shown. Each end carries three wheels, 100, 101, and 102, the first two running on top of a track 103 and the last one running under the track to hold the carriage on the track. Wheel 100 is flanged to fit the beveled upper edges of the track 103 for guiding the carriage sidewise. These tracks are fulcrumed at the rear end on studs 104 held in the frames. The front ends of these tracks are held by a pair of levers 105 (see Figure 9) and links 106 and are guided sidewise in slots 107 in the hubs of these levers. These levers are fixed to shaft 114. The height of the tracks is controlled by cam 108 and lever 109, with roll 110, and by link 111 connected to lever 105. The roll is held to the cam by spring 112 and poppet 113 in the frame. Parts 108, 109, 110, 111, 112, and 113 are not used on the rear side.

The carriage also carries a pair of short-toothed racks 115, which, while carried forward at cylinder speed, run into mesh with the gears 84 on the impression cylinder and hold the carriage in exact register with the cylinder while the sheet is being taken by the cylinder grippers. Then the cam 108 raises the tracks till the racks clear the cylinder gears. Then the carriage is reversed and returns clear of the sheet.

On the carriage bar 98 are carried a pair of registers, the front one being shown in Figures 21, 22, and 23. The rear register is the opposite hand to this and is not shown. These are each provided with front and side register stops 116 and 117 and friction elements 118 and 119 for pushing the sheet against the register stops. The register stops project downward through two of a number of openings 245 in the table 68 when the carriage is down for registering a sheet. The openings used depend on the width of the sheet to be printed. Openings 246 are to clear the cylinder grippers.

The friction elements are shown here as wheels which are set to rest lightly on the sheets, and they are partly rotated to bring the sheets against the register stops. Then, still turning, they slip on the sheet till they are raised as the sheet is taken by the cylinder grippers.

To get this rotation there is a cam 120 (see Figures 18, 19, and 20) fixed to the frame, and a lever 121 on the carriage with a roll 122 which runs up on the cam while the friction elements are resting on a sheet to carry it against the register stops. The lever 121 has a gear segment 123 meshing with a gear 124 attached by an overrunning clutch to shaft 125, which extends across the carriage through each register.

The overrunning clutch is shown in Figures 35 and 36, where 126 is a sleeve extending from the gear 124. A ratchet 127 is attached to the shaft by set screw 128 through collar 129. Each cut in the ratchet carries a small roller 130, which is slightly crowded between the sleeve and the ratchet by spring 131. This is a flat spring, somewhat curved, so that the ends press against a ratchet tooth and the middle, against the roller. This clutch turns shaft 125 anti-clockwise when roll 122 runs up on cam 120, but lets the shaft stand idle as spring 132 forces lever 121 and roll 122 to follow down the cam till stopped against pin 247 as the carriage returns. This allows the wear on the friction element to be distributed around the wheel instead of being repeated in one spot.

Figures 24 to 28 show alternate forms of the friction elements. In the first the friction surface is composed of fine sharp teeth formed on the metal surface of a wheel, while in the other the friction surface is a ring of rubber or of a similar material. If the driving mechanism were changed, the friction elements might be more like the rubber end on a lead pencil, which can illustrate the pushing of a sheet of paper over a smooth table by a friction element.

When shaft 125 is turned anti-clockwise, friction element 118 is turned clockwise by gear 133 keyed to the shaft and meshing with gear 134, which is combined with the friction element 118. In like manner, motion is conveyed to friction element 119 through bevel gears 135 and 136 and spur gears 137 and 138. Plate 139 is clamped under bar 98 by screws from a body 140, which carries part of the mechanism. This plate allows a clearance over the table for a sheet of

paper. The friction elements extend through openings in the plate to rest on the sheet of paper, a portion of which is shown as 141 registered against the front and side register stops, which are fastened to plate 139.

Friction element 118 and gear 134 run on stud 142 in lever 143, which is free on shaft 125. This lever has an extension 144 which holds a hollow screw 145 for regulating the pressure of a spring 146. This is guided by a pin 146' extending between the screw and body 140 to give the proper pressure of the friction element on the paper. This hollow screw is held from turning by tightening down screw 148. A stud 149 extends up from body 140 through 144 and carries a nut 150 to limit the swing of lever 143 when the friction element is not resting on a sheet of paper. Screw 151 can hold this nut from turning. The side register friction element 119 and associated parts 20 are like those just described. The spindle 152 running in body 140 carries the gears 136 and 137.

It will be noted that each register is provided with a side register stop and friction element. Only one side register can be used at a time. The stop not used can be removed and the corresponding friction element lifted clear of the sheet by turning down nut 150.

Figures 22 and 23 show a guide 244 for holding the sheet from buckling between the registers. As many of them may be used as are needed.

The sheet to be printed is so fed that it can be registered against the side register stop 117 close to the edge of one of the openings 245 in the table 68 as shown in Figure 23. The form is located on the plate, and the plate, on the cylinder to correspond closely with the sheet. Then the form is registered exactly by shifting the plate cylinder as shown in Figures 13 and 14, where 212 is the front end of the plate cylinder shaft. The bearings 168 are shown in these drawings as double-row preloaded ball bearings, and each bearing is clamped to the end of the shaft. The outside of this bearing is held in sleeve 213 by screw cover 214. This sleeve is fitted into the frame free to slide but held from turning by pin 215. The outer end of this sleeve has screw threads cut to fit internal threads which are cut in a sleeve 216 extending into the frame from gear 217. This gear can be turned by the pinion 218 shown integral with spindle 219. The gear and pinion are held against the frame by cover 220. Turning 219 by a crank adjusts sleeve 213 and the cylinder endwise as desired. The bearing in the rear frame can slide in the frame.

If a sheet is properly fed and registered, it is printed and delivered; but if a sheet is missed or if either edge lags back, it is electrically detected before reaching the impression cylinder; and this starts the mechanism for separating, or tripping, the blanket cylinder, first from the plate cylinder, and then from the impression cylinder. This prevents overinking the blanket or printing on the impression cylinder.

The parts for this detection are shown in Figures 1, 31, and 32, in which 153 is a still shaft extending across the press and held in two brackets 154 made from a material, such as Bakelite, that electrically insulates the shaft. Two wheels 155 of good electric conductivity run on pins 156 held in arms 157 located as desired on shaft 153. Each wheel 155 runs freely on a wheel 158 fixed on shaft 159, running in frames 71 and driven by gear 160 and intermediate gears 161 and 162 from gear 85. Gear 160 and wheel

158 extend up through openings in table 68, and the gear may have a cover 163.

Wheel 158 is composed of a hub 163, an insulating disc 164, and an electric contact part 165 of high conductivity. The contact part is clamped to the hub on the shaft and so is grounded to the frame. It has a small surface which comes in contact with wheel 155 once for each revolution unless insulated by an incoming sheet of paper. The leading edge of a properly fed sheet will cover this contact part and allow no electricity to pass, but if no sheet is fed, or if one or both edges lag back, an electric current of very brief duration can pass from a source of direct current 166 to shaft 153 through contact part 165 and be grounded on the press frame. As many wheels 158 may be mounted on shaft 159 as desired, and the two wheels 155 may be placed to run on two of the wheels 158 near the edges of the sheet being printed.

With regard to the tripping mechanism see Figures 4 and 11. A stirrup 167 supports the bearing 168 of the blanket cylinder and hangs vertically from the overhung ends of an eccentric spindle 169, which is carried in an eccentric bushing 170 in the frame and is operated by lever 182 on its outer end (see Figure 11). The stirrup has an outer part 171 with a sleeve passing through the frame in an opening larger than the sleeve, and it carries the bearing 168. An inner part 172, hanging from the inner end of the spindle, supports the inner end of the sleeve. These parts may be held together by washers 251 and 252 and sleeves 253 and 254. When this spindle is turned clockwise by the attached lever 182, the bearing is lowered, and the blanket cylinder is tripped clear of the plate cylinder.

Two links 173 and 174 are carried by the ends of a similar eccentric spindle 169' (see Figure 5) and extend horizontally to the left encircling the sleeve of the stirrup. When this spindle is turned anti-clockwise, the bearing is carried to the left, and the cylinder is tripped clear of the impression cylinder. The rear end of the blanket cylinder is supported in a similar way.

To operate these two tripping actions, the cam 175 is fastened to the end of the impression cylinder shaft. This cam has an easy lift for one-quarter turn, followed by a drop for one-quarter turn, and the high point is set about 45° ahead of the gripper edge of the cylinder. Lever 176, fulcrumed on stud 177, carries a roll 177' and is held against the cam by spring 178. The double-shouldered pushing connection 179 is connected to the outer end of this lever. Lever 180 carries two pins 184 and 185 and a guide plate 186 over 179. When connection 179 pushes on pin 184, it brings lever 180 and link 183 into straight toggle position (if they are not already so) with lever 182 and associated parts in printing position for the plate and blanket cylinders. When connection 179 is swung to the right, it contacts pin 185 and swings lever 180 to the left, breaking the toggle and tripping the blanket cylinder away from the plate cylinder.

Lever 187, connection 188, pins 189 and 190, shaft 191, and associated parts are similar to those just described. When connection 188 pushes pin 189, it brings lever 192 and link 193 into straight toggle position (if they are not already so) with the associated parts in printing position for the blanket and impression cylinders. When connection 188 is lifted, it pushes pin 190, breaking the toggle and tripping the blanket cylinder away from the impression cylinder. 75

Corresponding to levers 180 and 192 there are similar levers attached to the shafts 181 and 191 on the rear side of the press, but without the pins, and, as in common practice, the levers have springs and stop pins that hold them in either tripped or printing positions.

Lever 194 carries roll 195, which, pressed by spring 248, tends to follow cam 175 but may be held in high position by pawl 196 holding an arm 197 of this lever. In this position the cylinders run in printing contact. But if pawl 196 is lifted as an armature by the electromagnet 249 while the high point of the cam is under roll 195 (one-half turn from where shown), the roll will follow down the cam for one-quarter turn, and arm 198 of lever 194 through connection 199 will swing lever 200 to the right. Then this lever, working through connection 255, will swing connection 179 against pin 185 and, during the next quarter turn of the cam, will trip the blanket cylinder from the plate cylinder. During this tripping action, lever 201 will be swung clockwise by link 202 and will lift connection 203, thus bringing connection 188 against pin 190; and the next quarter turn of cam 175 will trip the blanket cylinder away from the impression cylinder, as the gaps of these cylinders are passing.

It will be noted that, to trip the press, pawl 196 must rise one-half turn before the position shown in the drawings, and connection 179 will be set for tripping the blanket cylinder from the plate cylinder during the next quarter turn. The tripping of the blanket cylinder from the plate cylinder occurs during the following quarter turn, being finished in the position in which the cylinders are shown (that is, just as the grippers are closed).

In Figure 9 this position is shown more clearly with the grippers 57 just closed. The gap in the blanket cylinder has passed the plate cylinder and is about to pass the impression cylinder while it is being tripped from the impression cylinder. The plate 204 is stretched on the plate cylinder by clamps 205, and the blanket 206 is held by reels 207. The gripper-operating lever 208 with roll 209 has just left the high part of cam 210 held to the frame by bracket 211.

Figure 12 shows some of the tripping parts in developed form in order to illustrate their relations to each other and to the frame.

I have described the electrical detection of a missed sheet, which starts the tripping action of the blanket cylinder. Alternating current will probably be supplied to drive this printing press. The electric current passing through the contact part 165 is so brief that if alternating current were used for the detection, the contact might be made while the voltage was zero, and no current would pass. Then again, the time may be too short to operate a relay to supply current to energize the electromagnet 249 for lifting pawl 196. Therefore I am using an electronic control which may be supplied by an electrical production company and placed in container 221. This will contain a rectifier to supply, from alternating power current, direct current of low voltage which may be grounded on the machine. This current supply will be used over line 166 in the detector, and the brief current from this will be used to excite an electronic tube which starts another direct current from the rectifier. This current will continue till broken by other means and in turn will be used to operate a relay to supply an alternating current from the power line for energizing

the electromagnet 249. This raises pawl 196 and allows the press to trip.

It may be found advisable to supply direct current enough to energize the magnet 197 without using a relay.

The detecting contact part 165, as shown, turns three times to each sheet fed, and so would allow three brief currents during each cycle if not insulated by a sheet. To prevent this, I ground the other end of the circuit for a sufficient time to start the trip, and then break the grounding during the other two contacts. The relay-operating current is also grounded on the machine. Figures 33 and 34 show the arrangement for grounding these currents only during the time required for starting the trip.

In this arrangement the double-ended lever 222 carries roll 223 running on cam 175 and is held to the cam by spring 224. An insulating block 225 is fastened to the frame and carries a flat conducting spring 226, to which is attached the combined terminal 227 of the currents to be grounded. This spring contacts lever 222 only when roll 223 is raised by the high part of the cam. The low part of the cam is shown by a full line as at the time of the grippers taking a sheet, but the high part of cam 175 and lever 222 in contact with spring 226 is shown in light lines composed of dashes as at the time for detecting and raising pawl 196. This contact grounds the currents.

The arrangement for detecting the absence of a sheet might have utilized the photoelectric cell, or the electric eye, but this also would have used an electronic control, and I prefer the arrangement shown. In either case, the electronic control is not a part of this invention.

The tripping arrangement which has been shown is fully automatic, depending on the absence or misplacement of a sheet, but there is also a manually-operated trip. In Figures 4, 6, and 7 the eccentric spindle 169 is held in eccentric bushing 170, which has an arm 228 controlling the position of the eccentric spindle 169. The position of this arm is held by crank 229 and connection 230. The effective length of this connection is adjusted by nuts 231 bearing against poppet 232 in arm 228. This length is set to cause bearers 250 of the cylinders to roll together and give printing contact. When lever 229 is turned over anti-clockwise, it lowers arm 228 and eccentric spindle 169 and separates the blanket cylinder from the plate cylinder. The automatic trip, if used in connection with the manual trip, would separate the cylinders still more. Shaft 233 extends through both frames and has similar parts at the rear end.

Eccentric spindle 169' is held in eccentric bushing 234, which, instead of having an arm as with 170, has a gear segment 235 meshing with a gear segment on lever 236 (see Figure 5). This lever can rock on a fixed sleeve 237 and extends downward, where it is adjusted by nuts 238 and held in position by crank 239, which, when turned anti-clockwise, separates the blanket cylinder from the plate cylinder. Fixed sleeve 237 with washer 256 also holds the bearing in the frame. Sleeve 240 clamps the bearing on the shaft and locates cam 175, which is held on by washer 241 and screw 242 and is kept from turning by key 243.

Having described my invention, what I claim is:

1. In a sheet-fed offset printing press, a plate cylinder, a blanket cylinder, and an impression cylinder; means for taking sheets at essentially

cylinder surface speed to the impression cylinder, means for detecting the absence or misplacement of a sheet before it should have reached the impression cylinder by the passage of a brief electric current between wheels running above and below the sheet path, and means initiated by the detecting means for automatically tripping the blanket cylinder from the plate cylinder, and then from the impression cylinder.

5 2. In a sheet-fed offset printing press with plate, blanket, and impression cylinders, means for feeding sheets at essentially cylinder surface speed from a sheet feeder to the impression cylinder, means located between the feeder and the impression cylinder for electrically detecting the absence of a sheet or an improperly fed sheet, a tripping mechanism initiated by the detecting means, for automatically tripping the blanket cylinder from the plate cylinder and then from the impression cylinder.

10 3. In a sheet-fed offset printing press having a plate cylinder, a blanket cylinder, and an impression cylinder, the plate and impression cylinders having fixed axes, means for automatically tripping the blanket cylinder from and to the plate cylinder and, from and to the impression cylinder, in each case tripping while the gaps of the adjacent cylinders are passing.

15 4. In a sheet-fed offset printing press having a plate cylinder, a blanket cylinder, and an impression cylinder, the plate and impression cylinders having fixed axes, means for supporting the blanket cylinder by stirrups hanging from eccentric spindles between the plate and blanket cylinder bearings in such a way that the rocking of the spindles will trip the blanket cylinder from or to the plate cylinder, and means for holding said blanket cylinder in relation to the impression cylinder by links from eccentric spindles located between the impression and blanket cylinder bearings in such a way that the rocking of the spindles will trip the blanket cylinder from or to the impression cylinder.

20 5. In a sheet-fed offset printing press having plate, blanket, and impression cylinders, a tripping mechanism including a single cam on the end of the impression cylinder shaft, with its followers arranged around the cam to be acted upon in sequence, so that it sets means for tripping the blanket cylinder from the plate cylinder, trips the blanket cylinder from the plate cylinder, and then trips the blanket cylinder from the impression cylinder.

25 6. In a sheet-fed offset printing press having plate, blanket, and impression cylinders, the plate and impression cylinders running on fixed axes, means for supporting the blanket cylinder from two pairs of eccentric spindles in such a way that rocking one pair of spindles will trip the blanket cylinder from the plate cylinder, and rocking the other pair of spindles will trip the blanket cylinder from the impression cylinder.

30 7. In a sheet-fed offset printing press with plate, blanket, and impression cylinders, means for automatically tripping the blanket cylinder in two directions by rocking eccentric spindles, eccentric bushings located in the frames and holding the eccentric spindles, and means for manually rocking the bushings to also trip the blanket cylinder.

35 8. In an offset printing press having plate, blanket, and impression cylinders, means for supporting the blanket cylinder in two directions from two sets of links in such a way that, by moving one set of links, the blanket cylinder is tripped from the plate cylinder, and then, by

moving the other set of links, initiated by the first tripping action it is tripped from the impression cylinder.

9. In an offset printing press having plate, blanket, and impression cylinders, the blanket cylinder being supported from a pair of eccentric spindles in such a way that rocking the spindles will move it from or toward the plate cylinder, and held from another pair of eccentric spindles in such a way that rocking these spindles will move it from or toward the impression cylinder.

10. In a sheet-fed offset printing press having plate, blanket, and impression cylinders, means for automatically tripping the blanket cylinder from the plate cylinder during the time that the gaps of these cylinders are passing the line connecting their centers; then, initiated by this tripping action, means for automatically tripping the blanket cylinder from the impression cylinder while the gaps of these cylinders are passing the line connecting their centers.

11. In a sheet-fed offset printing press having plate, blanket, and impression cylinders, means for electrically detecting the absence or misplace-

ment of a sheet before it should have reached the impression cylinder, and means, initiated by the detection, for automatically tripping the blanket cylinder from the plate cylinder and then initiated by this tripping action, means for tripping it from the impression cylinder.

12. In a printing press having plate, blanket, and impression cylinders, means for tripping the blanket cylinder out of cooperation with the plate and impression cylinders, including movable bearings for the blanket cylinder, first supporting members for each of the cylinder bearings, pivotally supported to swing the member toward and from the impression cylinder, second supporting members for each of the cylinder bearings, pivotally supported to swing the members toward and from the plate cylinder, and eccentrically formed pivots for the pivotally supported members, adapted to move the bearings and thus to move the cylinder into and out of cooperation with the plate and impression cylinders when the pivots are rocked.

IRVING A. HUNTING.
